Inventor
J. D. Winslow

UNITED STATES PATENT OFFICE.

JACOB D. WINSLOW, OF WILMINGTON, DELAWARE.

IMPROVEMENT IN FLOOR-CLAMPS.

Specification forming part of Letters Patent No. **59,305**, dated October 30, 1866.

To all whom it may concern:

Be it known that I, JACOB D. WINSLOW, of the city of Wilmington in the State of Delaware, have invented a new and Improved Floor-Clamp; and I do hereby declare that the following is a full, clear, and exact description of the construction and operation of the same, reference being had to the annexed drawings, making a part of this specification, in which—

Figure 1 is a floor plan, and Fig. 2 an elevation or perpendicular view.

My invention consists in providing a stout block of wood, *a*, with rounded ends, and furnished with iron hook-shaped dogs *b*, pointed for driving into the joist *e*, and working upon a pivot-bolt in the center of the block. This block is provided with lugs or ears *d d*, for keeping it in place upon the joist in operating.

In using this clamp, the block *a* is set upon the joist at the proper distance from the wedge *e*. The dogs *b b* are then driven into the joist

at the proper angle, and the boards sent home to their place by driving up the wedge *e*.

I am aware that joists have been used to clamp the floor in laying it down by boring a hole or holes and using iron pins and wedges; but this plan of mine differs entirely from all others.

I do not claim the dogs, block, or wedge, of themselves; but

What I claim as my invention, and desire to secure by Letters Patent, is—

The combination of the block *a*, composed of wood or other suitable material, (with or without ears or lugs *d d*), with the iron dogs *b b* and the wedge *e*, as hereinabove described, or any other appliances substantially the same, as and for a floor-clamp.

J. D. WINSLOW.
